(57) **CLAIM**

The ornamental design for a tossing ball with finned tail, as shown and described.

DESCRIPTION

FIG. 1 is a top front isometric view of the tossing ball with finned tail, showing the design.

FIG. 2 is a bottom rear isometric view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines in the drawings illustrate portions of the tossing ball with finned tail that form no part of the claimed design. Any shading is not a feature of the design but is included to illustrate the surface contours of the tossing ball with finned tail in the drawings.
